CLAIM

The ornamental design for a combined coaster and hood for removing smoke from ashtrays, as shown and described.

DESCRIPTION

FIG. 1 is a top perspective view of a combined coaster and hood for removing smoke from ashtrays, according to our new design;

FIG. 2 is a bottom perspective view thereof;

FIG. 3 is a rear elevational view thereof;

FIG. 4 is a right side elevational view thereof;

FIG. 5 is a front elevational view thereof;

FIG. 6 is a left side elevational view thereof;

FIG. 7 is a top plan view thereof;

FIG. 8 is a bottom plan view thereof; and,

FIG. 9 is a top perspective view illustrating our new design for a combined coaster and hood for removing smoke from ashtrays installed above a table surface.

The dotted lines showing of a table and ashtray in FIG. 9 are for illustrative purposes only and form no part of the claimed design.
